Application January 6, 1933, Serial No. 650,517

11 Claims. (Cl. 250—27)

My invention relates to control apparatus and has particular relation to apparatus for controlling the supply of power to a system of the type that is to be periodically energized and deenergized.

It is an object of my invention to provide control apparatus of a type wherein mechanical contacts shall not be utilized for a translating system that is to be periodically energized and deenergized.

Another object of my invention is to provide apparatus for controlling the condition of a translating system that is to be periodically deenergized and energized in which the lengths of the intervals during which the translating system is energized and deenergized shall be capable of any desired adjustment.

An incidental object of my invention is to provide an accurate time-delay element of simple structure.

According to my invention, I provide a control system of the type incorporating preferably a gas-filled electric discharge device having an anode, a cathode and a control electrode. The output circuit of the gas-filled device feeds the input circuit of a reactor, preferably of the inductive type. The output windings of the reactor are connected through the transmitting system to be controlled and supply power thereto.

A time constant circuit is coupled between the control electrode and the cathode of the electric discharge device, and its effect is to control the excitation of the electric discharge device.

The change in the condition of the electric discharge device is produced in the practice of my invention by varying the potential impressed between the control electrode and the cathode of the electric discharge device, between a maximum value and a minimum value as an alternating potential is impressed between the anode and the cathode. The electric discharge device is of such character that if an ordinary time-constant circuit were coupled to the electric discharge device in the usual manner, the electric discharge device would be energized and deenergized during periods corresponding to the half cycles of the potential impressed between the anode and the cathode thereof, and the periodicity of the excitation of the translating system would be equal to the periodicity of the source whereby potential is applied to the electric discharge device. An important feature of my invention resides in the fact that I have provided apparatus in which the intervals during which the electric discharge de-

vice is energized and deenergized may be adjusted to any desired value.

The novel features that I consider characteristic of my invention are set forth with particularity in the appended claims. The invention itself, however, both as to its organization and its method of operation, together with additional objects and advantages thereof, will best be understood from the following description of a specific embodiment when read in connection with the accompanying drawing, in which:

Figure 1 is a diagrammatic view showing a preferred embodiment of my invention;

Fig. 2 is a graph illustrating the operation of an electric discharge device of the type that is utilized in the practice of my invention; and,

Figs. 3, 4, 5 and 6 are graphs that will be utilized in explaining the changes introduced in the characteristic of the system by the various elements utilized in the practice of my invention.

The apparatus shown in Fig. 1 comprises an electric discharge device 1 of the gas-filled type. The anode 3 of the electric discharge device 1 is connected one bus line 5 of an alternating current power supply source (not shown) and the cathode 7 is connected to the other bus line 9 through the input circuit 11 of a three-legged core reactor 13. The cathode 7 is also coupled to the bus line 9 through a plurality of capacitors 15 and 17 and resistors 19, 21 and 23, and a rectifier 25. The resistors 19, 21 and 23 are connected in series with each other and in parallel with the input circuit 11 of the reactor 13, while the capacitors 15 and 17 and the rectifier 25 are connected in parallel with each other and each is in a separate series network with the input circuit 11. One terminal of one capacitor 15 is connected to one terminal of the outermost resistor 19; one terminal of the other capacitor 17 is connected between the resistor 19 and the central resistor 21 while the positive terminal of the rectifier 25 is connected between the resistor 21 and the resistor 23 which is connected directly to the bus line 9. It is to be noted that the rectifier 25 is conductive in the direction in which the arrow in Fig. 1 points.

The operation of my apparatus will be more clearly understood if it is noted that there are essentially three circuits involving the capacitors 15 and 17 and the resistors 19, 21 and 23. These circuits may be traced as follows:

(a) From the left-hand power line 5, through the discharge path between the anode 3 and the cathode 7 of the electric discharge device, the in-

put windings 11 of the reactor 13 to the other power line 9.

(b) From the power line 5, through the discharge path between the anode and cathode of the device 1, the capacitor 17, the resistor 21, the resistor 23 to the other power line 9.

(c) From the power line 5, through the discharge path between the anode and cathode of the device 1, the capacitor 15, the resistor 19, the resistor 21, the resistor 23 to the other power line 9.

The above described networks including the capacitors 15 and 17 and the resistors 19, 21 and 23 are coupled to the control electrode 27 of the electric discharge device 1 through an additional capacitor 29, a portion of the windings 31 of a secondary 33 of a transformer 35 the primary 31 of which is connected between the bus lines 5 and 9, and a grid-leak resistor 39.

20 The electric discharge device 1 is preferably of the type that has an energized and a deenergized condition and is capable only of abrupt transition from one condition to the other. Its manner of operation is best represented by a graph such as is shown in Fig. 2. In this view the potentials impressed between the electrodes 3, 7 and 27 of the electric discharge device 1 are plotted as ordinates against a time function which is plotted as abscissæ. The full-line curve 41 represents the 25 sinusoidal potential impressed between the principal electrodes 3 and 7 of the electric discharge device 1. This potential will be termed herein-after the principal potential. The broken-line curve 43 may be designated as the limiting control potential curve of the electric discharge device 1 and represents the boundary line of values of potential, impressed between the control electrode 27 and the cathode 7 of the electric discharge device 1, below which the device is in a 30 deenergized condition and above which the device is in an energized condition. That is to say, when the potential impressed between the control electrode 27 and the cathode 7 of the electric discharge device 1 is, at all times during any positive 35 half-cycle of the principal potential, of a value below the broken-line curve 43, the electric discharge device is in a deenergized condition. If this potential is raised to a value above the broken-line curve 43, the electric discharge device 1 is energized and remains energized, regardless of any subsequent variation in the control potential, until the principal potential is reduced to a value below the ionization potential of the electric discharge device. It is seen that the electric 40 discharge device may be periodically energized and deenergized by shifting the control potential from a value below the broken-line curve to a value above the broken-line curve. The periodicity of such excitation of the electric discharge device 1 by reason of the lock-in characteristic of the device can of course only be smaller than the periodicity of the principal potential. The periodic saturation of the reactor 13 and therefore the operation of the system is dependent on the periodic excitation of the electric discharge device 1.

From a consideration of Fig. 1 it can be seen that this object is accomplished principally by the charging and discharging of the capacitor 45 15 that is directly connected to the cathode 7. Normally the potentials impressed between the control electrode 27 and the cathode 7 of the electric discharge device 1 are adjusted to such values that when the capacitors 15 and 17 are in a substantially uncharged condition, the electric

discharge device 1 is energized. When it is thus energized, current is supplied through the electric discharge device 1 to the input winding 11 of the reactor 13 and the reactor is magnetically saturated. The output circuit 45 of the reactor 5 10 is coupled through the translating system 47 to be controlled which, as in the present case, may be a system of lamps 49 utilized in a display device such as an advertising sign for example. When the reactor 13 is magnetically saturated, the impedance of its output circuit 45 is low and the lamps 49 are energized.

However, at the same time that current is supplied to the input circuit 11 of the reactor 13 a difference of potential is established between the 15 terminals of the rectifier 25. During the half cycles of positive principal potential, therefore, the capacitors 15 and 17 are charged through the resistors 19 and 21 by reason of the difference of potential that exists between the terminals of 20 the rectifier 25. During the intervals of negative principal potential, during which the electric discharge device 1 is deenergized, the magnetic field built up by the current in the input circuit 11 begins to collapse, and a magnetizing current is accordingly induced therein, circulating through the resistor 23 and the rectifier 25. The magnitude of the potential impressed across the rectifier by reason of this current is considerably smaller than the magnitude of the potential by 30 reason of which the capacitors were charged and the mean effect of the complete cycle of principal potential is to impress a potential across the capacitors the polarity of which is the same as the polarity of the potential across the rectifier produced by the half-cycle of positive principal potential. Consequently, as long as the electric discharge device 1 remains in an energized condition the capacitors continue to be charged and the difference of potential between their plates continues to be increased, assuming that the charging period is not extended long enough for the capacitors to become fully charged.

It will be noted that one capacitor 15 is charged through the two resistors 19 and 21 in series, 45 while the other capacitor 17 is charged only through one resistor 21. The latter capacitor 17 will, therefore, be raised to a higher potential than the former capacitor 15 and the time required to raise the latter capacitor 17 to this 50 potential will be less than the corresponding time required for raising the first capacitor 15 to the corresponding potential. The relationship of the potentials impressed on the capacitors 15 and 17 is, of course, dependent on the magnitudes of the 55 capacitors. In the practice of my invention the capacitors 15 and 17 are preferably of equal magnitude.

The capacitor 15 when it is charged simulates a battery, the negative terminal of which is connected to the capacitor 29 and the positive terminal of which is connected to the cathode. Hence, as the potential difference between the plates of the capacitor 15 is increased, the potential of the control electrode 27 is decreased or rendered 60 more negative relative to the potential of the cathode 7. After an interval of time predetermined by the relative values of the resistors 19 and 21 and the first capacitor 15, the potential of the control electrode 27 is so decreased that 65 its value falls below the broken-line curve 43 of the graph shown in Fig. 2. If such a condition persists for the time occupied by more than one cycle of the principal potential the electric discharge device 1 is deenergized. When the electric 70 75

discharge device 1 is thus deenergized and the supply of current to the input circuit 11 of the reactor 13 is interrupted, the circulating magnetizing current in the circuit 11, 23, 25 dies out, and the impedance of the reactor 13 is correspondingly increased, thus deenergizing the illuminating units 49.

At the same time, the capacitor 15 would immediately begin to discharge through the resistors 19 and 21 and the rectifier 25, if the second capacitor 17 were not provided so as to maintain the capacitor 15 at the same or an even higher potential for at least a predetermined interval of time, as will subsequently be explained. If the second capacitor 17 were omitted, therefore, the first capacitor 15 would be discharged sufficiently to bring the control potential above the critical value 43, thus reenergizing the electric discharge device 1, almost immediately, or within a short interval of time after the potential of the control electrode 27 attains such a value that the electric discharge 1 is deenergized.

Since the capacitor 15 would thus be discharged within a short interval after the electric discharge device is deenergized, and since the electric discharge device is deenergized within a short interval after the control potential falls below the limiting control potential, a slight decrease in the charge impressed on the capacitor 15 would 30 revert the control potential to its initial value and the electric discharge device 1 would be reenergized as soon as the principal potential is of proper magnitude. The effect of such an arrangement would be such that the electric discharge device 1 would be deenergized for an interval of time corresponding approximately to only one negative half-cycle of potential impressed between its principal electrodes.

The second capacitor 17 is incorporated for the purpose of maintaining the first capacitor 15 in its charged condition for at least an interval of time, which may be explained as follows. When the electric discharge device 1 is energized, it conducts currents only during the positive half-cycles of principal potential, that is, when the left-hand bus-line 5 is positive and the right-hand bus-line 9 is negative. Under these conditions, the upper plates of the two capacitors 15 and 17 will be substantially at the potential of the positive bus-line 5 during the positive half-cycles, (there being only a small potential-drop in the discharge device 1), and the lower plates of the two capacitors will be connected, through the resistors 19, 21 and 23, to the other bus-line 9.

Since the lower plates of the two capacitors are connected to each other through the resistor 19, the charging of the first capacitor 15 will lag behind the charging of the second capacitor 17. When the lower plate of the first capacitor 15 reaches a sufficiently high negative charge relative to the cathode 1 (which is at the same potential as the upper plate of the capacitor 15), the electric discharge device 1 is deenergized, as previously explained. The second capacitor 17, being no longer connected to the bus-line 5 during the positive half-cycles of principal potential, immediately begins to discharge through the discharge-circuit 21, 25, but the first capacitor 15, being less highly charged, is at first at a smaller overall potential than the second capacitor 17, so that the first capacitor 15 still continues to charge until the two capacitors 15 and 17 are at the same voltage, whereupon the first capacitor 75 also begins to discharge, the discharging-circuit

including both resistors 19 and 21 and the rectifier 25.

When the first capacitor 15 is sufficiently discharged, the electric discharge device 1 will again be energized, as previously explained. But since 5 the second capacitor 17 has less resistance in its discharge-circuit than the first capacitor 15, it will have been discharging faster than the first capacitor 15, so that, at the moment of reenergization of the discharge device 1, the first capacitor 15 has a larger overall potential than the second capacitor 17, and the first capacitor will continue to discharge during the first part of the charging period of the second capacitor 17, or until the two capacitors are at the same overall 15 potentials.

In this way, it is possible to overshoot the critical grid-voltage line 43 by a considerable distance, thus avoiding "flashing" or energizing the electric discharge device every half-cycle, as 20 would have been the case if the second capacitor 17 had been omitted, as previously explained. The length of time for a complete cycle depends upon the values of the resistors 19 and 21 and the capacitors 15 and 17. It is seen that by utilizing 25 the second capacitor 17, the interval during which the electric discharge device 1 remains in deenergized condition may be considerably increased and any desired period of time may be attained during which the illuminating units 49 are deenergized. 30

The capacitor 29 that is connected between the first capacitor 15 and the control electrode 27 is charged from a potentiometer 51, that is energized from the secondary 33 of the transformer 25, across which it is connected through a rectifier 53, charging current flows in such direction that the capacitor-terminal nearest the control-electrode 27 is positive. The rectifier 53 is preferably a disk of the copper oxide type or of similar structure. It is to be noted that this capacitor 40 29, when once charged, will be maintained at a constant potential. The function of the capacitor 29 will be understood from a consideration of Figs. 3 and 4.

Fig. 3 shows the control-electrode potentials 45 when the capacitor 29 is absent from the system and the first capacitor 15 is directly connected to the control electrode 27, and Fig. 4 illustrates to the condition when the capacitor 29 is utilized. The broken-line curve 43 shown in Fig. 3 represents the limiting control potential with respect to the cathode-potential 55, and is the same as the curve 43 shown in Fig. 2. The horizontal lines 57 and 55 represent the maximum and minimum possible values of the control potential if 55 the first capacitor 15 were successively charged to its fullest extent and completely discharged again. It is seen that, when the capacitor 15 first begins to charge, the control potential quickly falls below the limiting control potential (represented by 60 the curve 43) and the electric discharge device 1 is deenergized at the end of the first half-cycle, and remains deenergized for an interval corresponding to capacitor 15 to return to a potential less (in amount) than the critical voltage 43. 65 During the half-cycle that the discharge device 1 is energized, the capacitor 15 is charged to a negative potential considerably higher (in amount) than the small critical value 43, and must return to this critical value before the discharge device 1 will again be energized. 70

In the tubes utilized in the practice of my invention the potential difference between the lowest point of curve 43 and line 55 is approximately 2 volts. As can be seen from Fig. 3, therefore, 75

the interval during which the electric discharge device 1 is energized is comparatively small while the interval during which the discharge device is deenergized is comparatively large. It is often 5 desirable, on the other hand, to more evenly distribute the periods during which the electric discharge device 1, and therefore the illuminating units 49, are energized and deenergized and for this reason the third capacitor 29, is introduced.

10 The capacitor 29 is ordinarily charged to a potential that is opposite in polarity to the potential impressed on the first and second capacitors 15 and 17 and the effect of so charging the capacitor 29 is to decrease the effective limiting 15 control potential and to drop the limiting control potential curve 43 to a position represented by the lower broken-line curve 59 as shown in Fig. 4. It is to be noted that, as the charge on the capacitor 15 is now varied from its minimum value 20 to its maximum value, the control potential passes through the limiting control potential values considerably later than it did in the system represented by Fig. 3, and the interval during 25 which the illuminating units are energized is considerably increased. By properly adjusting the movable tap 61 of the potentiometer 51, the relative proportions of the intervals during which the illuminating units 49 are energized and deenergized may be fixed at any desired 30 values.

35 The function of the third capacitor 29 may be perhaps more clearly understood by noting that the effect of charging the third capacitor 29 as shown in the drawing is to apply a positive charge to the control electrode 27. In view of the fact that such a positive charge is applied to the control electrode 27, the negative charge that must be applied to counteract the positive charge and to cause the electric discharge device 40 1 to become deenergized must be correspondingly greater than it would be if the capacitor were merely a conductor. Consequently, the ultimate result of utilizing the capacitor is to shift the limiting control potential curve 43 to a 45 lower position as already described.

50 In Figs. 5 and 6, the function of the alternating potential that is superposed by the windings 31 on the varying potential impressed through the capacitors 15 and 17 is illustrated. Fig. 5 shows the potentials obtained when the windings 31 are not present, and Fig. 6 corresponds to the condition represented in Fig. 1.

55 If the windings 31 were not present in the system, under conditions as represented in Fig. 5, an alternating potential is not superposed on the varying direct-current potential applied by the capacitors 15 and 17 and the ultimate result may be graphically represented simply by the movement of a horizontal line 63 from the minimum 60 value of control potential to the maximum value of control potential. It is to be noted, however, that the limiting control potential curve 43 is concave, substantially symmetrical about the maximum ordinate 62 of the curve 41 representing the corresponding half-cycle of principal potential. As the control potential is varied and the line 63 representing its variation moves upwardly from its lowest value, it first intersects the limiting control potential curve 43 at its central point and as it continues to move upwardly it intersects the curve 43 in regions further and further to the left, approaching the beginnings of the successive positive half-cycles 41, at the point at which the principal potential curve 41 70 intersects the time axis.

75 Thus it will be noted that as the control potential passes through the limiting potential the electric discharge device first becomes energized at a point corresponding to the point of intersection of the line 63 and the limiting potential 80 curve 43, and the electric discharge device continues to be energized during the remainder of that half-cycle. The magnitude of the current transmitted by the electric discharge device 1 is of course dependent on the point of intersection 85 of the line 63 and the curve 43. As the intersection point is moved towards the left the current output of the device is increased. The negative half-cycle of potential is next applied to the electric discharge device and the device remains 90 deenergized. During the interval following the first intersection of the straight line 63 and the curve 43, the straight line 63 continues to move upwardly, and when the positive half-cycle of potential is again applied to the electric discharge device, the potential applied to the control electrode 27 corresponds to a condition in which the straight line 63 intersects the broken-line curve 43 at two points 65 and 67 on both sides of the axis 62 of symmetry. It is seen 95 that by reason of the fact that the first intersection 65 is now towards the left of the axis 62 of symmetry, the output of the electric discharge device is increased over what it was during the preceding half-cycle.

100 The output of the electric discharge device 1 thus increases gradually when the control potential is increasing, and decreases gradually as the control potential decreases. The result of this condition is that the desired cut-off effects 105 are not produced, and the illuminating units 49 do not become energized and deenergized with the desired briskness, but rather fade in and fade out.

110 To obtain a highly desirable sharpness of operation, the alternating potential of the winding 31 is impressed on the varying control potential, and the resulting condition is represented graphically by curves such as are shown in Fig. 6. In this view the lower full-line curve 69 represents 115 the varying control potential which is composed of the alternating potential provided by the secondary section 31 of the transformer 35 and the varying potential provided through the capacitors 15 and 29. As the negative charge on the 120 capacitor 15 is decreased, the curve 69 is shifted from a position below the limiting control potential curve 43 to a position above the limiting control potential curve. It is seen that, as the curve 69 moves from its lower position to its upper position and passes through the limiting control position curve 43, it intersects this curve at 125 two points 71 and 73 adjacent to the points at which the principal potential curve 41 intersects the time axis. The corresponding physical condition is represented by a system in which the electric discharge device 1 when once energized 130 delivers substantially its maximum current output at once, and continues to deliver the maximum current output until the control potential is decreased to a value below the limiting control potential.

135 From the relationships shown in Fig. 6, it is evident that the winding 31, as represented by the resultant control-potential curve 69, is impressing a negative half-wave of potential on the control electrode 27 at the same time that the alternating-current source, as represented by the principal-potential curve 41, is impressing a positive half-cycle on the anode 3.

A specific system that I have found to be of considerable utility in the practice of my invention incorporates an electric discharge device 1 which is sold commercially under the name of 5 Grid-Glow tube KU-627. This device has an oxide-coated filament 7, and is capable of passing an average of approximately .64 ampere. The system is ordinarily energized from 110 volt, 60-cycle source which feeds the bus lines 5 and 9. 10 The capacitors 15 and 17 connected in series with the output of the electric discharge device are of the order of 2 microfarads, while the resistors 19 and 21 associated with the capacitors 15 and 17 may vary from $\frac{1}{2}$ megohm to 10 megohms. The 15 resistor 23 is of the order of 100 ohms. The capacitor 29 that is maintained in a constant charged condition is ordinarily of the order of $\frac{1}{2}$ microfarad and is maintained at a potential which may be varied from approximately zero to 50 volts, depending on the particular relationship that 20 is desired between the energized periods and the deenergized periods of the illuminating units 49. The alternating potential superposed on the varying potential by the winding 31 is of the order 25 of 5 volts, and the transformer 35 whereby the potential is applied is wound to yield this potential. The grid resistor 39 is of the order of 5 megohms.

My invention has been shown herein as applied 30 to a specific system. It is apparent that a number of modifications may be made without changing the essential features of my invention. For example, the asymmetric discharge device 1, that is shown as being utilized in the practice of my 35 invention and that is actually utilized, in the preferred practice of my invention, may be replaced by another asymmetric device. It may be replaced, for example, by a device incorporating two cathodes and a control electrode which is 40 adapted to pass current during both half cycles of the potential applied to the principal electrodes.

Moreover, while I prefer to utilize a gas-filled 45 electric discharge device in the practice of my invention, such a device is not absolutely essential and may be replaced by a high vacuum electric discharge device, or by a mercury pool device, or by other electric discharge devices of similar character.

Finally it should be noted that while my invention has been shown and described herein as applied to a load comprising illuminating units, it may be applied to a great number of other types of loads. I have, for example, found it to be 55 highly useful in the timing of the operation of spot-welding equipment.

Although I have shown and described certain specific embodiments of my invention, I am fully aware that many modifications thereof are possible. My invention, therefore, is not to be restricted except insofar as is necessitated by the prior art and by the spirit of the appended claims.

I claim as my invention:

1. In combination an electric discharge device 65 having an anode, a cathode and a control electrode, a capacitor connected in series with said anode and cathode and between said cathode and said control electrode, the connection in series 70 with said anode and cathode including a resistor connected in series with said capacitor, whereby said capacitor is charged through said resistor by the current transmitted between said anode 75 and cathode, and another capacitor connected in

series with said anode and cathode but shunting said first-named capacitor and said resistor.

2. In combination an electric discharge device 5 having an anode, a cathode and a control electrode, said device being of the type having an energized and a deenergized condition and being capable only of abrupt transition from one condition to the other, means for impressing a periodic potential between said anode and cathode, a capacitor connected in series with said anode 10 and cathode and between said cathode and said control electrode, a resistor connected in series with said anode and cathode and means, including means for impressing an alternating potential of uniform amplitude, coupled between said control electrode and said cathode, for energizing said discharge device precisely at a predetermined instant in each cycle of said periodic potential by applying potential between said control electrode and said cathode which is greater than 20 a predetermined critical value.

3. In combination with a voltage source, a first capacitor and means to control the rate of flow of a charging current to said capacitor from said source, a second capacitor connected to said first 25 capacitor through an impedance and means for charging it at such a rate that its voltage rise is more rapid than that of said first capacitor, and means for interrupting the flow of charging current from said source to both said capacitors 30 when said first capacitor is charged to a predetermined voltage.

4. In combination with a voltage source, a first capacitor and means to control the rate of flow of a charging current to said capacitor from said 35 source, a second capacitor connected to said first capacitor through an impedance and means for charging it at such a rate that its voltage rise is more rapid than that of said first capacitor, means for interrupting the flow of charging current 40 from said source to both said capacitors when said first capacitor is charged to a predetermined voltage, and means for gradually discharging said second capacitor.

5. In combination with a voltage source, a first 45 capacitor and means to control the rate of flow of a charging current to said capacitor from said source, a second capacitor connected to said first capacitor through an impedance and means for charging it at such a rate that its voltage rise 50 is more rapid than that of said first capacitor, means for interrupting the flow of charging current from said source to both said capacitors when said first capacitor is charged to a predetermined voltage, means for gradually discharging 55 said second capacitor, and means for restarting the flow of charging current to said capacitors when said first capacitor is charged to a predetermined voltage.

6. In combination with an electrical discharge 60 device having an anode, a cathode and a control electrode, a capacitor having one of its terminals connected to said cathode and its other terminal connected to a load circuit supplied with current by said device, a connection from the last-named terminal of said capacitor to said control electrode, and means for discharging said capacitor when said discharge tube is substantially non-conductive at a rate slower than the charging rate of said capacitor when said discharge tube 70 is conductive.

7. In combination with an electrical discharge 75 device having a pair of principal electrodes and a control electrode, means for impressing a periodic voltage between said principal electrodes,

5 a timing circuit comprising a capacitor connected in circuit between said control electrode and one of said principal electrodes, a rectifier and an impedance connected to charge said capacitor by means of current flowing through the principal electrodes of said discharge device, and a second capacitor connected in shunt around said impedance and said first capacitor.

8. In combination with a source of periodic voltage, an electrical discharge device having a pair of principal electrodes and a control electrode, a timing circuit comprising a capacitor connected in circuit between said control electrode and one of said principal electrodes, a rectifier and an impedance connected to charge said capacitor by means of current flowing through the principal electrodes of said discharge device, a second capacitor connected in shunt around said impedance and said first capacitor, and a constant potential source connected in series in the circuit between said first capacitor and said control electrode.

9. In combination with a source of periodic voltage, an electrical discharge device having a pair of principal electrodes and a control electrode, 25 a timing circuit comprising a capacitor connected in circuit between said control electrode and one of said principal electrodes, a rectifier and an impedance connected to charge said capacitor by 30 means of current flowing through the principal electrodes of said discharge device, a second capacitor connected in shunt around said imped-

ance and said first capacitor, and a source of periodic voltage of the same frequency as said first-named source connected serially in the circuits with said first capacitor and said control electrode.

10. In combination with a voltage source, a first capacitor and means to control the rate of flow of a charging current to said capacitor from said source, a second capacitor connected to said first capacitor and means for charging it at such a rate that its voltage rise is more rapid than that of said first capacitor, and means for interrupting the flow of charging current from said source to both said capacitors when said first capacitor is charged to a predetermined voltage. 15

11. In combination with a voltage source, a first capacitor and means to control the rate of flow of a charging current to said capacitor from said source, a second capacitor connected to said first capacitor and means for charging it at such a rate that its voltage rise is more rapid than that of said first capacitor, means for interrupting the flow of charging current from said source to both said capacitors when said first capacitor is charged to a predetermined voltage, means for discharging said capacitors at a predetermined rate and means for interrupting the charging current from said source to said capacitors after said first capacitor has been discharged to a predetermined voltage. 20 25 30

WILLIAM W. VIEBAHN.
